(57) **CLAIM**

The ornamental design for a portable computer, as shown and described.

DESCRIPTION

FIG. 1 is a front perspective view of a first embodiment of a portable computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view thereof, taken along lines 8-8 in FIG. 6;

FIG. 9 is an enlarged partial section view of FIG. 8;

FIG. 10 is a front perspective view of a second embodiment of the portable computer;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a cross-sectional view thereof, taken along lines 17-17 in FIG. 15; and,

FIG. 18 is an enlarged partial section view of FIG. 17.

The even-dash broken lines in the drawings illustrate portions of the portable computer that form no part of the claimed design. The dash-dot broken lines represent the directions of the section cuts and form no part of the claimed

(Continued)

design. The dash-dot-dot broken lines indicate the sections shown in the enlarged partial section views and form no part of the claimed design.

1 Claim, 18 Drawing Sheets
